WEEDER

John B. Bellin, West Los Angeles, Calif., assignor of one-half to Charles Gentilini, Los Angeles, Calif.

Application August 8, 1955, Serial No. 37,350

Term of patent 14 years

(Cl. D35—2)

Fig. 1 is a side elevational view of a weeder, showing my new design.

Fig. 2 is a front elevational view thereof.

Fig. 3 is an enlarged cross-sectional view taken on the plane 3—3 of Fig. 2, and looking in the direction of the arrows.

I claim:

The ornamental design for a weeder, substantially as shown.
